UNITED STATES PATENT OFFICE.

JOHN D. MORGAN, OF SUMMIT, AND LOUIS A. HAWTHORNE, OF NEWARK, NEW JERSEY,
ASSIGNORS TO STEEL UTILITIES, INCORPORATED, A CORPORATION OF NEW YORK.

METAL-WORKING MACHINE.

1,241,263.

Specification of Letters Patent. Patented Sept. 25, 1917.

Application filed April 1, 1915. Serial No. 18,502.

To all whom it may concern:

Be it known that we, JOHN D. MORGAN, of Summit, New Jersey, and LOUIS A. HAWTHORNE, of Newark, N. J., citizens of the 5 United States, have made Improvements in Metal-Working Machines, of which the following is a specification.

The invention relates to machines for punching structural shapes and like work, 10 and more particularly to machines for traveling and successively stopping the shape in position to be punched at the desired points; through the instrumentality of settable and automatically operating distance 15 determining devices; and relates further to novel means and mechanisms for rapid and precise alternate traveling and stopping of the work so that the holes may be punched therein with great rapidity and accuracy 20 and at any desired distances apart from fractions of an inch to many feet. Further objects of the invention will be set forth in part hereinafter and in part will be obvious herefrom.

25 The invention consists in the novel parts, constructions, combinations and improvements herein shown and described.

30 The accompanying drawings referred to herein, and constituting a part hereof, illustrate one embodiment of the invention, and together with the description serve to explain the principles thereof.

Of the drawings:

35 Figure 1 is a fragmentary top plan of a machine constructed in accordance with the principles of the invention;

Fig. 2 is a fragmentary plan, on an enlarged scale, of the lower central part of Fig. 1, with certain parts broken away;

40 Fig. 3 is a central vertical section corresponding generally to Fig. 2, and looking therat from the upper side of the sheet;

Fig. 4 is an end elevation looking at Fig. 2 from the left, or at Fig. 3 from the right, with certain parts in section and others 45 broken away;

Fig. 5 is a transverse vertical section substantially centrally of Figs. 2 or 3 and looking in the same direction as Fig. 4;

50 Fig. 6 is an elevation showing two distance determining devices working alternately from a single distance record setting or controlling sheet;

Fig. 7 is a horizontal section through the timing device for setting the interponents 55 for the distance in feet, the rack with the teeth on top;

Fig. 8 is a vertical section on the line C—D of Fig. 7 looking in the direction of the arrows;

Fig. 9 is a fragmentary elevation looking at Fig. 7 from the foot; and

Fig. 10 is a diagram of the single distance record sheet alternately controlling two distance determining devices.

In the exemplified embodiment of the accompanying drawings, the work to be operated upon is shown in the form of an I-beam α . In the embodied form of traveling or progressing means for the work, the beam α rests upon a substantially horizontal series of rollers 1, which rollers are driven to progress or travel the beam α relatively to the punching mechanism. The rollers 1 are journaled in bearings 2 upon the machine 75 frame 3. Fixed to the shafts of the rollers 1 are beveled gears 4, which beveled gears intermesh with corresponding beveled gears 5, which are fixed upon shafts 6. The shafts 6 are shown on each side of the punch 80 housing 10 and they are driven in a suitable manner, as by the spur wheel 7 shown fixed to the right hand shaft 6 in Fig. 1. Gear 7 meshes with a pinion 8 upon the shaft of a motor 9. The punching means, or the 85 location thereof is indicated in a general manner by the housing 10.

In the particular form of progressing means embodied herein, the beam or shape α is urged or impelled forward by the rotation of the rolls 1 and is permitted to so move forward or is restrained from so doing by the action of a suitable distance determining means, although the invention in many of its aspects may be employed 90 with other forms of beam or shape progressing means. The embodied form of means acting directly to permit and prevent the progressing of the shape α and the consequent positioning thereof relative to the tool 100 equipped means comprises a head 15 having connections to the distance determining means, the forward end of the beam α pressing against the head 15 and thus remaining in constant relation or contact therewith. 105 The head 15 is attached to a long, horizon-

tally arranged rail or bar 16 extending backwardly alongside the shape or beam α . The distance determining means engages with the rail or bar 16 to accurately position the work α relatively to the punching mechanism. The present embodiment of the invention will be regarded as arranged to operate for feet, inches and sixteenths-of-an-inch.

In accordance with certain features of the invention, distance determining devices operating alternately and successively are employed, one such device serving to position the shape for one punching, and the other device positioning the shape for the next successive punching, thus the one device may be setting or set to position the shape while the other device is recovering or returning preparatory to its next setting. This will save a great deal of time and result in an increase of speed and a consequent increase in product. In accordance with certain features of the invention such mechanism or means is designed to operate with or be controlled by a distance record sheet or like device, that is, a sheet in which the distance values for successive punchings are preliminarily marked or indicated, the machine recognizing the successive distance values so marked and indicated, and positioning the work accordingly for punching.

In the embodied form, these features of the invention are applied to or included in a distance determining mechanism wherein a member, such as the rail or bar 16, traveling with the shape or beam is provided with engaging devices spaced apart in distances equal to the larger distance values or denominations and an interponent or stop is projected into the path of travel of such engaging devices at such time as to engage a particular one of said engaging devices to permit of the right distance or amount of travel of the work corresponding to the particular setting or reading of the distance determining means. In connection therewith, the lesser distance values or denominations are supplied or effected in the positioning of the work by varying the position of the interponent along the path of travel of the engaging devices.

In addition to these features of the invention, other features are embodied and realized, as will in part be particularly pointed out hereinafter, and all of which are realized by the means pointed out in the appended claims, and are exemplified in the embodied form.

Referring now more particularly to the embodied form and considering primarily at this time a single distance determining device, and also considering the means for varying the longitudinal position or location of the interponent along the path of travel of the engageable member, the rail or bar 16

(see Figs. 1 and 3) is provided on its upper surface with lugs 20 which are a uniform and predetermined distance apart preferably one foot apart from the engaging face on one lug to the engaging face on the next lug. The bar 16 slides along and is supported by suitable bearings 21 in the machine frame, and it may rest or ride upon suitable rollers or other friction reducing bearings (not shown).

Mounted upon the machine frame, or otherwise secured in fixed position relatively to the punching means or other tool equipped means, is a fixed bearing face 22. Mounted upon suitable supports is a fixed or supporting shaft 23, shown with its ends bearing on supports 24 and 25. A dowel pin 26 keeps the shaft 23 from rotation. Rotatably mounted upon the shaft 23 is a cylinder 27, which is rotatable in proportion or conformity to the desired distance setting, to vary the longitudinal position of the interponent which engages the selected lug 20 at each distance setting. The left hand end of shaft 23 in Fig. 3 is squared or otherwise shaped to preserve the interponent carrier 28 in erect or fixed position thereon, while the interponent carrier is slidably longitudinally of the shaft, and may conveniently pass through a slot 43 in the shaft.

Suitable means are provided for causing the interponent carrier to vary its longitudinal position in conformity to the rotation of the cylinder 27. For this purpose the left hand end of the cylinder 27 in Fig. 3 is provided with an inclined or graduated cam face 29 against which the surface 30 of interponent carrier 28 contacts or rides, whereby the interponent is moved longitudinally to correspond to the inches and sixteenths of the various and successive distance settings. The interponent 31 is slidably mounted within the carrier 28 and is projectable into and retractable from engaging position with the space lugs 20 upon the bar or rail 16. The interponent 31 is shown held in retracted position by a spring 32 and as being projectable into engaging position by a solenoid 33 mounted in the interponent carrier 28. The interponent 31 is connected by a rod 34 with the core 35 of the solenoid. The winding of the solenoid is connected by suitable circuits to the settable devices such as a distance record sheet and a suitable timing mechanism.

Means are provided for causing the interponent carrier to follow the cam surface 29 of the positioning cylinder 27, and as embodied, such means comprises a groove cam 36 on the interior surface of the cylinder 27. Into this groove cam 36 projects a finger 38, which is carried on a rod 39. The rod 39 is longitudinally slidable in an aperture 40 in the interponent carrier 28. The

rod 39 is acted on by a spring 41, which is in compression between the interponent carrier and a nut 42 threaded on the rod 39. Thus the interponent carrier will follow the cylinder 27 during the restoring movement and also during the setting movement and will avoid slamming or loose movement and the consequent shock when the interponent engages the lug for which it is set.

10 In the embodied form of means for rotating and stopping the cylinder 27, means are provided which tend to continuously rotate the cylinder, the embodied form thereof comprising an annular series of gear teeth 50 formed in the outer wall of the cylinder 27. Meshing with said gear teeth 50 is a pinion 51, which is loose upon a shaft 52, but having a spring operated friction clutch connection therewith. In the embodied 15 form of clutch connection, the pinion 51 on one side faces upon a collar 53, and upon its opposite side the pinion 51 faces a collar 54 loose upon shaft 52. The collar 54 is acted upon by a spring 55 coiled about shaft 52 20 and in compression between the collar 54 and a collar 56 fixed on the shaft 52. The shaft 52 is carried in suitable bearings 57 and 58 formed on the supporting pillars or brackets 59 and 60. The shaft 52 has fixed 25 thereto a sprocket wheel 61 over which passes a sprocket chain 62 said chain running also over a sprocket wheel 63 fixed on the shaft of a motor 64.

The embodied form of means for permitting or preventing rotation of the cylinder 27 and setting it for different desired distances includes arcuate grooves 66 formed in the exterior wall of the cylinder 27, and of such length and position as to give or 30 permit the desired amount of rotary movement to the cylinder. Coöoperating with the respective grooves 66 are corresponding rows or series 67 of pins which are projectable into and retractable from the grooves 66. 35 These pins are automatically controlled and preferably are controlled by a distance record device through suitable means such as corresponding series of solenoids 68. Each of the pins 67 as shown is held in retracted 40 position by spring 69, the solenoids 68 when energized acting to set or project the corresponding pin into the slot. The solenoids may be in circuit with a suitable automatic distance record device 140 to effect the successive 45 settings of the cylinder. The initial position of the cylinder when it is restored or returned may be effected or determined by a solenoid operating in the manner described, or in the reverse manner, or by a 50 suitable spring device, or other like means employed for this purpose.

In the embodied form a further movement of the cylinder 27 is effected after the pin 67 representing the desired distance de-

nomination, such as one or more inches, has 65 been projected into its corresponding groove 66 and has reached the stopping position at the end of the groove. Such further rotation or movement is imparted to the cylinder 27 to set the interponent for the sixteenths- 70 of-an-inch, and in accordance with one feature of the invention this is effected by also moving the pin or pins 67 together with the cylinder 27. In the embodied form, the pins 67 reciprocate in apertures in a plate 75 80, of partially cylindrical form and conforming substantially to the surface of the cylinder 27. The plate 80 is fixed to the member 81, which has a bearing surface 82, against which bearing surface the end of 80 the cylinder 27 bears, the member 81 having also a bearing surface 83, which bears on the stationary surface 22. The member 80 is mounted or journaled on the shaft 23 and is in fixed position longitudinally of the 85 shaft and has a partial swinging or rotative movement about the shaft. In the embodied form, the pins 67 effect the setting in inches, and the member 81 is permitted sufficient swinging movement to effect the setting for 90 the additional sixteenths. For the purpose of effecting this setting there are formed in the cylindrical surface of the member 81, a series of apertures 85 which are positioned and proportioned to effect the corresponding 95 additional feed for the sixteenths-of-an-inch. Projectable into and retractable from the apertures 85 are a series of pins 86, which are impelled retractably by springs 87, and are projected into their apertures 100 selectively by solenoids 88, in like or similar manner with the solenoids 68 previously described. The pins 86 and solenoids 88 are carried upon a plate 89 fixed to the support or pillar 60 upon which the bearing surface 105 62 is borne.

The manner of operation of the device may be generally stated as follows:—

The proper solenoid 68 and the proper solenoid 88 for the desired number of inches and sixteenths having been selected and energized the so-called zero pin or like device will release the cylinder 27, which thereupon will begin to rotate by reason of the driving of pinion 51. When the set pin 69 reaches the end of its slot in the corresponding groove 66, the plate 80 and pin 69 will then rotate with cylinder 27 to effect the feeding or setting for the additional sixteenths over the integral inch, the member 81 having likewise been released from its detent and free to move for a distance determined by the set pin 86. During the rotation of the cylinder 27, the finger 38 following the cam groove 36 causes the 115 detent carrier 28 to move longitudinally of shaft 23 a corresponding number of inches and sixteenths-of-an-inch. The detent 120 125 31

is then projected before the proper engaging lug 20 to give the proper number of feet of travel to the work, such projection of the 5 detent 31 being controlled by mechanism later to be described. During the restoring movement of the cylinder 27, the member 81 is likewise restored through suitable means such as a spring 90.

The form of means which controls the 10 action of the interponent 39 to effect the setting for the desired number of feet (shown generally in Fig. 1 and in detail in Figs. 7, 8 and 9, and diagrammatically in Fig. 10) comprises settable traveling devices 15 having settings representing feet, such devices traveling proportionately to the travel of the shape x . As embodied, a rack 100 is formed upon the rail 16 with which rack meshes a pinion 101, said pinion being fixed 20 on shaft 102. Shaft 102 is conveniently journaled in a bearing 202 and in the housings 117 and 118. A pinion 103 also on shaft 102 meshes with external teeth 105 on an internally and externally geared ring 25 104. Internal teeth 106 on said gear ring 104 mesh with a pinion 107 fixed on a shaft 108 which shaft 108 is carried on an arm 113, which arm is supported on bushing 125 and on shaft 102. A gear 109 is fixed on the 30 opposite end of shaft 108, said gear meshing with teeth 110 on the hub of a disk 111. The disk 111, gear 104 and disk 126 are rotatively mounted on, but electrically insulated from shaft 144 by a bushing 115. 35 Shaft 144 is fixed in the housing 117 and 118. The housing 117 carries ten contact plungers or pins 119, mounted in insulated bushings 120. On the insulating bushings 120 are a series of open contacts 220, which are closed 40 by enlargements 221 on the plungers 120 (see Figs. 7 and 10). The plungers or pins 119 are equally spaced circumferentially around the face of housing 117, the intervening spaces representing feet of travel of 45 rack 100 and of the shape x , as measured by travel of disk 111.

The contact plungers or pins 119 are set by solenoids 121, which solenoids are supported by plate 150 on upper portion of 50 housing 117. On disk 111 is mounted a copper segment 123, insulated therefrom, but having electrical contact with a disk 122, which disk is fixed to a sleeve 124. The sleeve 124 is internally insulated from shaft 55 114 by the bushing 115, and is externally insulated from disk 111, and from arm 113, gear 104 and disk 112 by a bushing 125. The disk 112 carries a copper segment 127 insulated from the disk and electrically connected with a disk 126, which disk is fixed to the sleeve 124. Contact plungers or pins 60 128 are mounted in insulating bushings 129, carried in housing 118. On the insulating bushings 129 are a series of open contacts

229, which are closed by enlargements 228 65 on the plungers 128 (see Figs. 7 and 10). Said pins 128 are actuated and controlled by solenoids 162. The contact plungers 128 are equally spaced circumferentially on the face of the housing 118, the intervening 70 spaces representing tens of feet of travel of the rack 100.

The manner of operation of the foregoing mechanism in recording or setting the required distance for the feet and tens of feet 75 part of the distance, so as to project the interponent 31 into engaging position with the proper lug 20, is substantially as follows:

Suppose a distance of thirty-three feet is 80 to be traveled or measured before the circuit is closed to project the interponent 31. The key or pin of the series 119 which corresponds to the numerical value of 3, and the key or pin of the series 128, which corresponds to the numerical value of 30 are for 85 instance set on a keyboard, or are represented by corresponding perforations in a distance record sheet, whereby the proper circuit connections are made to energize the corresponding solenoid of the series 121 to 90 set the three foot contact key or pin of the series 119 and the corresponding solenoid of the series 128 which sets the thirty foot key or plunger 129. The closing of the contacts 220 and 229 corresponding to the set 95 plungers 119 and 128, respectively, energizes the contact points carried by these respective plungers, in position to complete the circuit when the contact points on both set plungers 119 and 128 simultaneously are in 100 contact with their respective rotating segments 123 and 127. The timer is thus set and as the bar 100 travels forward, the pinion 101 rotates therewith. The movement is transmitted therefrom to the gear 105 ing already described, rotating disk 111 one revolution for each ten feet of travel of bar or rack 100, and rotating disk 112 one revolution for each one hundred feet of rack 110 travel.

Disk 111 will make contact between its copper segment 123 and the three foot set pin when the rack 100 has moved three feet, also again when it has moved thirteen feet, also at twenty-three feet and again at thirty- 115 three feet of the movement of the rack 100. During this time the circuit has been open at disk 112. The disk 122 has its copper segment 127 electrically connected in series with the disk 111, and disk 112 will close 120 the circuit when the rack 100 has traveled thirty feet. There is a gap however in the circuit at the disk 111 until the three foot contact closes this gap, and thus the two gaps in the circuit are only closed at thirty- 125 three feet of travel of the rack 100. At this juncture, the circuit being complete, the solenoid 33 is energized, and the interponent

31 is projected into the path of the proper contact lug 20. The inches and fractions of an inch of the distance is controlled by the longitudinal movement of the interponent carrier 28 as already described. Thus the complete setting for the entire distance is effected, and the shape properly and accurately positioned to be punched.

In accordance with certain features of the invention, as already indicated, a plurality of distance determining devices are alternately operated, and such arrangement is shown in Figs. 1 and 6 of the drawings and diagrammatically in Fig. 10 although it will be understood that the invention in many of its aspects is applicable to a single distance determining device operating alone, or a plurality of such devices operating together.

In the embodied form of plural or alternate operation, each mechanism may be substantially alike, so far as its principal features of construction and operation are concerned. In the two devices shown, the cylinders 27 are shown oppositely disposed, as will be clear from Figs. 1 and 6, whereby with the use of one common drive therefor, one cylinder can be making a setting while the other is restoring for a succeeding setting, the consequent over-lapping of the 30 times in the cycle operation of the respective devices, effecting a great saving of time and consequent increase of product.

In accordance with one feature of the invention, means are provided whereby the controlling circuit for two distance determining devices are successively cut in and cut out so that upon successive settings only one series of solenoids or other controlling devices is energized or set while the other device is restoring preparatory for a new setting. In Fig. 10 of the drawings a distance record sheet 140 is shown having cooperating sets of contacts 141, 142 which are permitted to close their respective circuits by the occurrence of properly located perforations in the sheet 140 (the contacts being held apart by the sheet and the circuits remaining open when the perforations do not occur). Thus by the automatic feed of the distance record sheet the successive distance settings are effected. In Fig. 10 there is also shown a diagrammatic layout of one form of circuit wiring or arrangement suitable for the machine, although so far as concerns many features of the invention, any suitable arrangement or system of wiring may be employed. The timer dials *a* and *aa* represent the dials in the machine for the feet and tens of feet, and showing for each of the dials one of the solenoid operated contact plungers marked respectively by reference numerals 121 and 162. *b*, *c* represent the inches and sixteenths-of-an-inch, respectively, of one of

the distance determining devices, one of 65 the solenoids 68 and one of the solenoids 88 being shown coöperating therewith. The inch and sixteenth-of-an-inch controls of the other or alternate distance determining device are indicated respectively as *b'* and *c'*, and one each of the corresponding solenoids are indicated respectively as 68' and 88'. *d* and *e* represent electro-magnetic switches which may be of the ordinary relay type. *f* and *g* represent the interponents of 70 the two distance controlling devices, which are marked 31 in the drawings of the mechanism, and which engage with the lugs on the rail 16. *M* represents the motor which drives the distance determining mechanisms, and which is marked 64 in the drawings of the machine. *s* represents a four arm, double throw switch, and *B'* and *B²* represent sources of electric current for the various 80 circuits.

Let it be assumed by way of example, that the distance record sheet 140 presents to the contacts perforations for a feed of the work amounting to twenty-one feet, three and five sixteenths inches, and that the various contacts, solenoids and stop pins shown are those corresponding to such reading. The two distance determining devices being oppositely constructed as heretofore explained, one will be restoring preparatory to being reset, while the other of said devices is advancing to a setting. On the next feed of the machine, and with the arrangements shown, the motor *M* is reversed, and the contrary conditions obtain, respectively, as to the setting and restoring of the distance determining devices.

The perforations in the sheet 140 permitting the circuits to close, and considering the closed contacts from the left hand toward the right, current from the source *B'* flows through the first closed contact into the timer solenoid *aa* which sets the requisite solenoid for the tens of feet, namely the "twenty" solenoid, the current returning through the solenoid to source *B'*. Considering now the second contact from the left on the sheet 140, the closing of this contact causes the current to flow through and energize the solenoid coöperating with disks *a* for the proper "units" of feet, namely the "one". The circuit returns from the solenoid to the source *B'*. The third contact allows the current to pass to the corresponding solenoid 68 and 68' to set *c* and *c'* for the "three" inch stop pins of both devices, the circuit continuing to the opposite terminals of the switch *s*, shown at the right hand side of the switch in Fig. 10.

Assuming the switch *s* to be closed below and open above, the solenoid 68 of the device *c*, which connects to the upper switch termi-

nal will carry no current on account of the switch being open, and, therefore, the solenoid will not be energized nor will the corresponding distance pin be set. The 5 corresponding solenoid for the distance determining device c' , having circuit connections to the lower terminal of switch s is energized by reason of the current flowing therethrough and through the switch s . The 10 "three" inch stop pin 68' of device c' is therefore set. The fourth or right hand contact on sheet 140 sets for the "sixteenths" of an inch, and allows current to pass to the solenoids 88 and 88', alternately depending 15 upon the position of the switch s , operating in the same manner as explained above in connection with respective solenoids 68 and 68'. The motors 9 driving the rolls 1 act to 20 propel the beam π forward, rotating the timer in harmony therewith. When the timer reaches the point where the twenty foot contact and the one foot contact are closed simultaneously, as already described 25 in connection with the mechanism, a path is provided for the current to both of the interponent solenoids f and g . The negative sides of the solenoids are wired to opposite terminals of the switch s , the solenoid f being connected to the upper terminal is 30 inoperative, under the setting of the switch previously assumed, while the solenoid g , connected to the lower terminal of switch s , completes its circuit through s and back to 35 the source of energy. The setting of the interponent g closes the relay circuit controlling switch h and thereby allows current to flow through the coils of relay e . Relay e closes the circuit through switch s 40 at the lower contact to start the driving motor for the distance determining devices and the device $b' c'$ advances until held by the set pins at the proper settings of three inches and five sixteenths of an inch. The 45 punching mechanism now operates, and the switch s is reversed by any suitable mechanism, and it may be arranged to be reversed by the back stroke of the punch. The distance record sheet 140 is fed forward 50 preparatory to a repetition of the operation described. On the next operation, however, the device $b' c'$ and the interponent g are quiescent or on dead circuits and the device $b c$ and the interponent f are active and in circuit on the upper contacts of switch s . The remainder of the operation 55 will be readily understood as already stated. When interponent f is set or energized, the relay circuit control i will energize relay d which will close the circuit for motor M in the reverse direction, or with opposite polarity, thus reversing the direction of movement of the distance determining devices, and setting the device b, c and re- 60 65 storing the device $b' c'$ preparatory for

the next setting. Thus there is alternate operation or setting of the two distance determining devices, effected automatically by the machine itself, when the switch s is mechanically operated as described. It will be 70 understood that the motor M will have suitable windings for the particular kind of work as will be clearly understood by those skilled in the art.

So far as concerns the location of the 75 timer interponents longitudinally of the rail 16, they have been shown one after the other and arranged in the same direction. It will be clear, however, that they could be arranged in various ways, as for 80 instance, one of them could be turned end for end and their interponents be positioned to engage the rail at the same point, or they could be arranged symmetrically side by side, or in various ways. Different arrangements of wiring and of timing contacts could be also utilized, the principle of operation in all such cases remaining the same.

From all the foregoing it will be understood 90 that mechanism has been provided realizing the objects of invention and the advantages herein pointed out together with other objects and advantages. It will be further understood that changes may be 95 made from the illustrated and described form without departing from the principles of the invention and without sacrificing its chief advantages.

What we claim as our invention and desire to secure by Letters Patent is:—

1. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism. 105

2. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and settable means controlling said distance determining devices. 115

3. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and a 125 130

- single settable means controlling a plurality of said distance determining devices.
4. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and a single settable means controlling alternately a plurality of said distance determining devices.
5. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and settable means controlling said distance determining devices operating alternately thereon.
6. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and automatic controlling means for said distance determining devices.
7. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and electrically operating automatic controlling means for said distance determining devices.
8. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and automatic controlling means for said distance determining devices, said controlling means including a distance record device, and electrical connections therefrom to said distance determining devices.
9. A machine for punching structural shapes including in combination punching mechanism, means for successively traveling and stopping the shape in desired positions relatively to the punching mechanism, said
- means including a plurality of distance determining devices operating alternately to stop and position the shape relatively to the punching mechanism and automatic controlling means for said distance determining devices, said controlling means including a distance record sheet and electrical circuits opened and closed thereby.
10. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and automatic controlling means for said distance determining devices, said controlling means including a perforate distance record sheet and connections between the sheet and said distance determining means and coöperating with said perforations.
11. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism, and electrically operating settable means controlling said distance determining devices.
12. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism, and electrically operating settable means controlling said distance determining devices operating alternately thereon.
13. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and a single electrically operating settable means controlling a plurality of said distance determining devices.
14. A machine for punching structural shapes including in combination punching mechanism, means for successively traveling and stopping the shape in desired positions relatively to the punching mechanism, said means including a plurality of distance determining devices operating alternately to

stop and position the shape relatively to the punching mechanism and a single controlling means for a plurality of said distance determining devices.

5 15. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and a single controlling means for a plurality of said distance determining devices and operating to set one distance device while another distance device is restoring.

10 16. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism and a single controlling means for a plurality of said distance determining devices, said controlling means including a distance record device.

15 17. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism, and a single controlling means for a plurality of said distance determining devices, said controlling means including a perforate distance record device.

20 18. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and a single controlling means for a plurality of said distance determining devices, said controlling means including a perforate distance record sheet.

25 19. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and a single controlling means for a plurality of said distance determining devices, said controlling means

including a distance record device and electrically operating connections from said distance record device to each of said distance determining devices.

30 20. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism, and a single controlling means for a plurality of said distance determining devices, said controlling means including a distance record sheet, and electrically operating connections from said distance record sheet to each of said distance determining devices.

35 21. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism, and a single controlling means for a plurality of said distance determining devices, said controlling means including a perforate distance record sheet and connections from said distance record sheet to each of said distance determining devices.

40 22. A machine for punching structural shapes including in combination punching mechanism, means for successively traveling and stopping the shape in desired positions relatively to the punching mechanism, said means including a plurality of distance determining devices operating alternately to stop and position the shape relatively to the punching mechanism and a single controlling means for a plurality of said distance determining devices, said controlling means including a perforate distance record sheet and electrically operating connections from said distance record sheet to each of said distance determining devices.

45 23. A machine for punching structural shapes including in combination punching mechanism, and means for successively traveling and stopping the shape in desired positions relatively to the punching mechanism, said means including a plurality of distance determining devices operating alternately to stop and position the shape relatively to the punching mechanism, and a single controlling means for said plurality of distance determining devices and rendered alternately operative and inoperative relatively to the respective distance determining devices.

50 24. A machine for punching structural shapes including in combination punching mechanism, means for successively traveling

and stopping the shape in desired positions relatively to the punching mechanism, said means including a plurality of distance determining devices operating alternately to 5 stop and position the shape relatively to the punching mechanism, and a single controlling means for said plurality of distance determining devices including electrical circuits to the different distance determining 10 devices and means for rendering the respective electrical circuits alternately alive and dead.

25. A machine for punching structural shapes including in combination punching mechanism, means for successively traveling and stopping the shape in desired positions relatively to the punching mechanism, said means including a plurality of distance determining devices operating alternately to 20 stop and position the shape relatively to the punching mechanism, and a single controlling means for said plurality of distance determining devices including electrical circuits to the different distance determining 25 devices and automatically operating means for rendering the respective electrical circuits alternately alive and dead.

26. A machine for punching structural shapes including in combination punching mechanism, means for successively traveling and stopping the shape in desired positions relatively to the punching mechanism, said means including a plurality of distance determining devices operating alternately to 30 stop and position the shape relatively to the punching mechanism, and a single controlling means for said plurality of distance determining devices, said controlling means comprising a single distance record device 35 and connections therefrom to each of the distance determining devices, and means for rendering said respective connections alternately operative and inoperative.

27. A machine for punching structural shapes including in combination punching mechanism, means for successively traveling and stopping the shape in desired positions relatively to the punching mechanism, said means including a plurality of distance determining devices operating alternately to 45 stop and position the shape relatively to the punching mechanism, and a single controlling means for said plurality of distance determining devices, said controlling means comprising a single distance record device 50 and electrically operating connections therefrom to each of the distance determining devices, and means for rendering said respective connections alternately operative 55 and inoperative.

28. A machine for punching structural shapes including in combination punching mechanism, means for successively traveling and stopping the shape in desired positions 60 relatively to the punching mechanism, said

means including a plurality of distance determining devices operating alternately to stop and position the shape relatively to the punching mechanism, and a single controlling means for said plurality of distance 70 determining devices, said controlling means comprising electrical circuits to each distance determining device and a circuit making and breaking distance record device, and means for making the circuits to the respective distance determining devices alternately 75 dead and alive.

29. A machine for punching structural shapes including in combination punching mechanism, means for successively traveling and stopping the shape in desired positions relatively to the punching mechanism, said means including a plurality of oppositely 80 acting distance determining devices moving simultaneously one to and one from determining position with respect to the work and alternately acting to determine successive stops and positions of the work relatively to the punching mechanism.

30. A machine for punching structural shapes including in combination punching mechanism, means for successively traveling and stopping the shape in desired positions relatively to the punching mechanism, said means including a plurality of oppositely 85 acting distance determining devices moving simultaneously one to and one from determining position with respect to the work and alternately acting to determine successive stops and positions of the work relatively to the punching mechanism and a single controlling means for both distance 90 determining devices.

31. A machine for punching structural shapes including in combination punching mechanism, means for successively traveling and stopping the shape in desired positions relatively to the punching mechanism, said means including a plurality of oppositely 95 acting distance determining devices moving simultaneously one to and one from determining position with respect to the work and alternately acting to determine successive stops and positions of the work relatively to the punching mechanism and a single controlling means for both distance 100 determining devices, said controlling means including a distance record device.

32. A machine for punching structural shapes including in combination punching mechanism, means for successively traveling and stopping the shape in desired positions relatively to the punching mechanism, said means including a plurality of oppositely 120 acting distance determining devices moving simultaneously one to and one from determining position with respect to the work and alternately acting to determine successive stops and positions of the work relatively to the punching mechanism, and a 125

- single controlling means for both distance determining devices, said controlling means including an electrically operating distance record sheet.
33. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism and a single controlling means for both distance determining devices, said controlling means including a perforate distance record device.
34. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism, and a single controlling means for both distance determining devices, said controlling means including settable devices coöperating with each distance determining device.
35. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism and a single controlling means for both distance determining devices, said controlling means including settable devices coöperating with each distance determining device, and a common distance record device for setting said settable devices.
36. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism, and a

- single controlling means for both distance determining devices, said controlling means including electrically operating devices co-operating with each distance determining device.
37. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism and a single controlling means including electrically operating settable devices coöperating with each distance determining device and a common distance record device for setting said settable devices.
38. A machine for punching structural shapes including in combination punching mechanism, and means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism and a single controlling means for both distance determining devices, said controlling means including settable devices coöperating with each distance determining device, and a common perforate distance record device for setting said settable devices.
39. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism and a single controlling means including electrically operating settable devices coöperating with each distance determining device and a common perforate distance record device for setting said settable devices.
40. A machine for punching structural shapes including in combination punching mechanism, means for successively traveling and stopping the shape in desired positions relatively to the punching mechanism, said means including a plurality of oppositely acting distance determining devices rotating simultaneously one to and one from

ing with each distance determining device and a common distance record device for setting said settable devices.

49. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism, and a single controlling means for both distance determining devices, said controlling means including settable devices coöperating with each distance determining device and electrical circuits for said respective settable devices and a distance record device for selectively making and breaking the circuits.

50. A machine for punching structural shapes including in combination punching mechanism, means for successively traveling and stopping the shape in desired positions relatively to the punching mechanism, said means including a plurality of oppositely acting distance determining devices moving simultaneously one to and one from determining position with respect to the work and alternately acting to determine successive stops and positions of the work relatively to the punching mechanism, and a single controlling means for both distance determining devices, said controlling means including settable devices coöperating with each distance determining device and electrical circuits for said respective settable devices and an intermittently fed distance record device for selectively making and breaking the circuits.

51. A machine for punching structural shapes including in combination a circuit making and breaking distance record sheet, a plurality of movable distance determining members, electro-magnetic devices acting respectively to position said distance determining members, electrical circuits between said electro-magnetic devices, and said distance record sheet, and means for cutting in or out the circuit to either distance record device.

52. A machine for punching structural shapes including in combination a circuit making and breaking distance record sheet, a plurality of movable distance determining members, electro-magnetic devices acting respectively to position said distance determining members, electrical circuits between said distance record sheet, and means acting alternately for cutting in or out the circuit to either distance record device.

53. A machine for punching structural

shapes including in combination punching mechanism, an engageable member traveling with the work, and an interponent movable into engagement with said engageable member to stop and position the work, a distance record device, and means controlled thereby for causing the engagement of said interponent with said engageable member, and means for rendering said engagement causing means inoperative.

54. A machine for punching structural shapes including in combination punching mechanism, an engageable member traveling with the work, a plurality of interponents separately movable into engagement with said engaging means to stop and position the work.

55. A machine for punching structural shapes including in combination punching mechanism, an engageable member traveling with the work, a plurality of interponents separately movable into engagement with said engaging means to stop and position the work and means for selectively causing either of said interponents to engage the engaging means.

56. A machine for punching structural shapes including in combination punching mechanism, an engageable member traveling with the work, a plurality of interponents separately movable into engagement with said engaging means to stop and position the work and means for alternately causing either of said interponents to engage the engaging means.

57. A machine for punching structural shapes including in combination punching mechanism, an engageable member traveling with the work, a plurality of interponents separately movable into engagement with said engaging means to stop and position the work and means for selectively causing one and preventing another of said interponents to engage the engaging means.

58. A machine for punching structural shapes including in combination punching mechanism, an engageable member traveling with the work, a plurality of interponents separately movable into engagement with said engaging means to stop and position the work irrespective of the amount of intervening travel of the work.

59. A machine for punching structural shapes including in combination punching mechanism, an engageable member traveling with the work, a plurality of interponents separately movable into engagement with said engaging means to stop and position the work and means for selectively causing either of said interponents to engage the engaging means irrespective of the amount of intervening travel of the work.

60. A machine for punching structural shapes including in combination punching mechanism, an engageable member traveling

with the work, a plurality of interponents 5 separately movable into engagement with said engaging means to stop and position the work and means for alternately causing either of said interponents to engage the engaging means irrespective of the amount of intervening travel of the work.

61. A machine for punching structural shapes including in combination punching 10 mechanism, an engageable member traveling with the work, a plurality of interponents separately movable into engagement with said engaging means to stop and position the work and means for selectively 15 causing one and preventing another of said interponents to engage the engaging means irrespective of the amount of intervening travel of the work.

62. A machine for punching structural 20 shapes including in combination punching mechanism, a plurality of distance determining devices alternately enlarging and diminishing in size to effect successive positionings of the work relatively to the punching mechanism.

63. A machine for punching structural 25 shapes including in combination punching mechanism, a plurality of distance determining devices alternately enlarging and diminishing in length to effect successive positionings of the work relatively to the punching mechanism.

64. A machine for punching structural 30 shapes including in combination punching mechanism, a plurality of distance determining devices alternately enlarging and diminishing in size to effect successive positionings of the work relatively to the punching mechanism and means automatically 35 controlling said changes in size.

65. A machine for punching structural 40 shapes including in combination punching mechanism, a plurality of distance determining devices alternately enlarging and diminishing in size to effect successive positionings of the work relatively to the punching mechanism and electrically operating means automatically controlling said changes in size.

66. A machine for punching structural 45 shapes including in combination punching mechanism, a plurality of distance determining devices alternately enlarging and diminishing in length to effect successive positionings of the work relatively to the punching mechanism and means automatically controlling said changes in length.

67. A machine for punching structural 50 shapes including in combination punching mechanism, a plurality of distance determining devices alternately enlarging and diminishing in length to effect successive positionings of the work relatively to the punching mechanism and electrically operating means automatically controlling said changes 55 in length.

68. A machine for punching structural shapes including in combination punching 60 mechanism, a plurality of distance determining devices alternately enlarging and diminishing in size to effect successive positionings of the work relatively to the punching mechanism and means automatically controlling said changes in size, said means including a distance record device.

69. A machine for punching structural 65 shapes including in combination punching mechanism, a plurality of electrically operating distance determining devices alternately and successively enlarging and diminishing in size to effect successive positionings of the work relatively to the punching mechanism, said means including a distance record device.

70. A machine for punching structural 70 shapes including in combination punching mechanism, a plurality of distance determining devices alternately enlarging and diminishing in size to effect successive positionings of the work relatively to the punching mechanism, said means including a distance record device.

71. A machine for punching structural 75 shapes including in combination punching mechanism, a plurality of distance determining devices alternately enlarging and diminishing in length to effect successive positionings of the work relatively to the punching mechanism and means automatically controlling said changes in length, said means including a distance record device.

72. A machine for punching structural 80 shapes including in combination punching mechanism, a plurality of distance determining devices alternately enlarging and diminishing in length to effect successive positionings of the work relatively to the punching mechanism, and electrically operating means automatically controlling said changes 85 in length, said means including a distance record device.

73. A machine for punching structural 90 shapes including in combination punching mechanism, a plurality of distance determining devices alternately enlarging and diminishing in size to effect successive positionings of the work relatively to the punching mechanism and electrically operating means automatically controlling said changes 95 in size, said means including a perforate distance record device.

74. A machine for punching structural 100 shapes including in combination punching mechanism, a plurality of distance determining devices alternately enlarging and diminishing in length to effect successive positionings of the work relatively to the punching mechanism, and means automatically controlling said changes 105 in length, said means including a perforate distance record device.

75. A machine for punching structural 110 shapes including in combination punching mechanism, a plurality of oppositely acting 115 distance determining devices alternately enlarging and diminishing in size to effect successive positionings of the work relatively to the punching mechanism.

76. A machine for punching structural 120 shapes including in combination punching mechanism, a plurality of oppositely acting 125 distance determining devices alternately enlarging and diminishing in size to effect successive positionings of the work relatively to the punching mechanism.

shapes including in combination punching mechanism, a plurality of oppositely acting distance determining devices alternately enlarging and diminishing in length to effect successive positionings of the work relatively to the punching mechanism.

76. A machine for punching structural shapes including in combination punching mechanism, a plurality of oppositely acting distance determining devices alternately enlarging and diminishing in size to effect successive positionings of the work relatively to the punching mechanism and means automatically controlling said changes in size.

77. A machine for punching structural shapes including in combination punching mechanism, a plurality of oppositely acting distance determining devices alternately enlarging and diminishing in size to effect successive positionings of the work relatively to the punching mechanism and means automatically controlling said changes in size.

78. A machine for punching structural shapes including in combination punching mechanism, a plurality of oppositely acting distance determining devices alternately enlarging and diminishing in length to effect successive positionings of the work relatively to the punching mechanism and means automatically controlling said changes in length.

79. A machine for punching structural shapes including in combination punching mechanism, a plurality of oppositely acting distance determining devices alternately enlarging and diminishing in length to effect successive positionings of the work relatively to the punching mechanism and means automatically controlling said changes in length.

80. A machine for punching structural shapes including in combination punching mechanism, a plurality of oppositely acting distance determining devices alternately enlarging and diminishing in size to effect successive positionings of the work relatively to the punching mechanism and means automatically controlling said changes in size, said means including a distance record device.

81. A machine for punching structural shapes including in combination punching mechanism, a plurality of oppositely acting distance determining devices alternately enlarging and diminishing in size to effect successive positionings of the work relatively to the punching mechanism and means automatically controlling said changes in size, said means including a distance record device.

82. A machine for punching structural shapes including in combination punching mechanism, a plurality of oppositely acting distance determining devices alternately

enlarging and diminishing in length to effect successive positionings of the work relatively to the punching mechanism and means automatically controlling said changes in length, said means including a distance record device.

83. A machine for punching structural shapes including in combination punching mechanism, a plurality of oppositely acting distance determining devices alternately enlarging and diminishing in length to effect successive positionings of the work relatively to the punching mechanism, and electrically operating means automatically controlling said changes in length, said means including a distance record device.

84. A machine for punching structural shapes including in combination punching mechanism, a plurality of oppositely acting distance determining devices alternately enlarging and diminishing in length to effect successive positionings of the work relatively to the punching mechanism, and means automatically controlling said changes in length, said means including a perforate distance record device.

85. A machine for punching structural shapes including in combination punching mechanism, a plurality of distance determining devices alternately enlarging and diminishing in size and interponents movable with the respective distance determining devices, and an engageable device, with which the interponents may engage, traveling with the work to effect successive positionings of the work relatively to the punching mechanism.

86. A machine for punching structural shapes including in combination punching mechanism, a plurality of distance determining devices alternately enlarging and diminishing in length and interponents movable with the respective distance determining devices, and an engageable device, with which the interponents may engage, traveling with the work to effect successive positionings of the work relatively to the punching mechanism.

87. A machine for punching structural shapes including in combination punching mechanism, a plurality of distance determining devices alternately enlarging and diminishing in size and interponents movable with the respective distance determining devices, and an engageable device, with which the interponents may engage, traveling with the work to effect successive positionings of the work relatively to the punching mechanism and means automatically controlling said changes in size.

88. A machine for punching structural shapes including in combination punching mechanism, a plurality of distance determining devices alternately enlarging and diminishing in size and interponents movable with the respective distance determining devices,

and an engageable device, with which the interponents may engage, traveling with the work to effect successive positionings of the work relatively to the punching mechanism and electrically operating means automatically controlling said changes in size.

89. A machine for punching structural shapes including in combination punching mechanism, a plurality of electrically operating distance determining devices alternately and successively enlarging and diminishing in size and interponents movable with the respective distance determining devices, and an engageable device, with which the interponents may engage, traveling with the work to effect successive positionings of the work relatively to the punching mechanism.

90. A machine for punching structural shapes including in combination punching mechanism, a plurality of distance determining devices alternately enlarging and diminishing in length and interponents movable with the respective distance determining devices, and an engageable device, with which the interponents may engage, traveling with the work to effect successive positionings of the work relatively to the punching mechanism and means automatically controlling said changes in length.

91. A machine for punching structural shapes including in combination punching mechanism, a plurality of distance determining devices alternately enlarging and diminishing in size and interponents movable with the respective distance determining devices, and an engageable device, with which the interponents may engage, traveling with the work to effect successive positionings of the work relatively to the punching mechanism and means automatically controlling said changes in size, said means including a distance record device.

92. A machine for punching structural shapes including in combination punching mechanism, a plurality of oppositely acting distance determining devices alternately enlarging and diminishing in size and interponents movable with the respective distance determining devices, and an engageable device, with which the interponents may engage, traveling with the work to effect successive positionings of the work relatively to the punching mechanism.

93. A machine for punching structural shapes including in combination punching mechanism, a plurality of oppositely acting distance determining devices alternately enlarging and diminishing in length and interponents movable with the respective distance determining devices, and an engageable device, with which the interponents may engage, traveling with the work to effect successive positionings of the work relatively to the punching mechanism.

94. A machine for punching structural

shapes including in combination punching mechanism, a plurality of oppositely acting distance determining devices alternately enlarging and diminishing in size and interponents movable with the respective distance determining devices, and an engageable device, with which the interponents may engage, traveling with the work to effect successive positionings of the work relatively to the punching mechanism and means automatically controlling said changes in size.

95. A machine for punching structural shapes including in combination punching mechanism, a plurality of oppositely acting electrically operating distance determining devices alternately and successively enlarging and diminishing in size and interponents movable with the respective devices, and an engageable device, with which the interponents may engage, traveling with the work to effect successive positionings of the work relatively to the punching mechanism.

96. A machine for punching structural shapes including in combination punching mechanism, a plurality of oppositely acting distance determining devices alternately enlarging and diminishing in length and interponents movable with the respective distance determining devices, and an engageable device, with which the interponents may engage, traveling with the work to effect successive positionings of work relatively to the punching mechanism and means automatically controlling said changes in length.

97. A machine for punching structural shapes including in combination punching mechanism, a member movable with respect to a fixed surface to change its distance determining effect, an interponent moving in fixed relation with said movable member, and an engageable member traveling with the work.

98. A machine for punching structural shapes including in combination punching mechanism, a member rotatable with respect to a fixed surface to change its distance determining effect, an interponent moving in fixed relation with said rotatable member, and an engageable member traveling with the work.

99. A machine for punching structural shapes including in combination punching mechanism, a member movable with respect to a fixed surface to change its distance determining effect, an interponent moving longitudinally in fixed relation with said movable member, and an engageable member traveling with the work.

100. A machine for punching structural shapes including in combination punching mechanism, a member movable with respect to a fixed surface to change its distance determining effect, an interponent moving in

fixed relation with said movable member, and an engageable member traveling with the work, and means for projecting said interponent into the path of said engageable 5 means.

101. A machine for punching structural shapes including in combination punching mechanism, a member movable with respect to a fixed surface to change its distance determining effect, an interponent moving longitudinally in fixed relation with said movable member, and an engageable mem-

ber traveling with the work and means for projecting said interponent into the path of said engageable means. 15

In testimony whereof, we have signed our names to this specification, in the presence of two subscribing witnesses.

JOHN D. MORGAN.
LOUIS A. HAWTHORNE.
